UNITED STATES PATENT OFFICE.

JOHN M. MIDDLETON, OF SAVANNAH, GEORGIA.

RULE.

1,160,432.

Specification of Letters Patent. Patented Nov. 16, 1915.

Application filed February 11, 1915. Serial No. 7,546.

To all whom it may concern:

Be it known that I, JOHN M. MIDDLETON, a citizen of the United States of America, residing at 237 East Gordon street, Savannah, in the county of Chatham and State of Georgia, have invented certain new and useful Improvements in Rules, of which the following is a specification, reference being had therein to the accompanying drawing.

10 This invention relates to folding rules and the like and has for its object the production of a simple and efficient means whereby a center is produced upon the rule along the one inch mark to permit the operator to 15 place his dividers upon the rule in an efficient manner to set the dividers at the proper gage without injuring the rule or marring the face thereof.

Another object of this invention is the 20 production of a simple and efficient plug which is adapted to be placed within the rule to permit the dividers to be readily set therein for the purpose of obtaining the desired gage.

25 With these and other objects in view this invention consists of certain novel combinations, constructions, and arrangements of parts as will be hereinafter fully described and claimed.

30 In the accompanying drawing, Figure 1 is a plan view of the rule. Fig. 2 is a perspective view of one end of the rule in a folded position. Fig. 3 is an enlarged sectional view through the rule showing the manner 35 in which the plug is placed therein. Fig. 4 is a detail perspective of the plug detached from the rule.

Referring to the drawing it will be seen that 1 designates the body of the rule which 40 may be formed in any desired manner, such as for instance as a folding rule, straight edge rule, square, or other suitable instrument without departing from the spirit of the invention. The body 1 is provided with 45 a transversely extending aperture 2, within which is placed a metallic plug 3 preferably formed of brass or other suitable material for accomplishing the desired result. The plug 3 is provided at each end thereof 50 with inwardly extending conical sockets 4, which sockets 4 have their side walls extending at a slight angle to produce a shallow socket at each end of the plug. The side walls of the socket 4 terminate short of the 55 periphery of the plug 3 so as to produce a flat marginal edge 5 along the side edges

thereof, which marginal edges 5 are adapted to fit flush with the respective top and bottom edges of the body 1 of the rule. It should be understood that the plug 3 is 60 placed within the aperture 2 formed in the rule at a proper distance along the first longitudinally extending line for indicating the inner end of the sixteenth inch marks upon the edge of the rule, and it should be understood that the plug 3 is also placed along any line with the one inch mark 6 of the rule clearly illustrated in Fig. 2 and also in Fig. 1, so as to have the apex 7 of the conical socket 4 direct in line with the one inch 70 mark.

It is a well known fact and well recognized that all users of a rule for measuring or obtaining the desired gage by means of a pair of dividers will begin from the one inch 75 mark upon the rule owing to the fact that the edge or end of the rule very often becomes worn or injured, and in this manner will result in an inaccurate measurement. By placing the plug 3, however, upon the one 80 inch mark this difficulty may be overcome, and it should be further understood that the socket 4 by being formed very shallow and having the apex 7 thereof in direct alignment with the one inch mark, the point of 85 the dividers may be readily seated therein in order to have a substantial anchor for the dividers while the proper distance or gage is obtained by spreading the respective arms of the dividers. It should be further understood that owing to the fact that the sockets 90 4 are formed very shallow, the dividers can be spread quite a distance and will have the points thereof register with the apex of the socket 4 which is a very essential point, for 95 if the points of the dividers were to engage the side walls of the socket 4 an inaccurate measurement would result. The inclination of the sides will cause the point of the dividers to be seated within the apex 7 of the 100 socket.

It should be further understood that the flat marginal edges 5 around the edge of the socket 4 will act as a protector means for preventing the dividers while being placed 105 within the socket 4 from injuring the wooden portion of the rule.

It should be borne in mind that the present device may be applied to any suitable instrument, geometrical instruments, such as 110 a rule, square, or other measuring device wherein an anchoring means is used, and it

should be understood that the present device is susceptible of being applied direct to a wooden rule without the necessity of adding considerable weight or additional expense in 5 constructing the rule, and in this manner doing away with the necessity of employing an entire metal rule. It should be understood that the present device may be applied to the rule which is now in use, and that the 10 plug 3 may be removed if so desired for the purpose of renewing the plug should one of the plugs become injured.

Having thus described the invention what is claimed as new, is:—

15 As a new article of manufacture, a wooden rule provided with a plurality of gradu-

tions formed near the side edge thereof, a metallic plug passing transversely through said rule adjacent the edge thereof and registering with one of the graduations, said 20 plug provided at each end with a substantially inverted cone-shaped pocket, said plug also provided with a flat rim adjacent the periphery thereof, said rim adapted to extend flush with the outer faces of said rule. 25

In testimony whereof I hereunto affix my signature in presence of two witnesses.

JOHN M. MIDDLETON.
